DES. N° 1154

U.S. 1154

Roswell Kimberly, of Ansonia, Conn.
Letters Patent No. 1154. Dated Oct. 11. 1859.

The schedule referred to in these Letters Patent, and making part of the same.

To all whom it may concern:

Be it known that I, Roswell Kimberly, of Ansonia, in the County of New Haven, and State of Connecticut, have invented a new Design for Clock Cases, &c., and I do hereby declare that the following is a full, clear, and exact description of the construction and character of the same; reference being had to the accompanying drawing which makes a part of this specification, which drawing is a plan, or direct view of the front of the case, exhibiting, or representing the New Design.

I make the Clock Case of wood, or any other suitable material.

I make the lower portion of the Case in the form represented in the drawing, or in any other of the well known forms, or otherwise, and make the parts plain, or ornamental, as taste may dictate, or the Market require.

I make the upper portion of the Case of a semi-octagonal form, as shown at A. B. & C. combined with the corner Blocks D. & E. and the Tops, F. & G. surmounting the

2

Wes. 1154

the corner Blocks, all as represented in the drawing.

I am aware that octagonal bases are, and have been, in common use, and that corner Blocks may be as old as Cases themselves; and that the Tips were perhaps the first ornaments which were put upon a Case; and that corner Blocks and Tips have often been used together. I therefore do not claim either of these alone, nor the corner Blocks and Tips combined, as my invention, or New Design, - but

What I claim as my invention and desire to secure by Letters Patent, as a New Design, is the Semi-Octagonal top in combination with the corner Blocks and Tips, when the whole is constructed, arranged, and made to present the symmetry of the New Design, as herein described and represented.
